METHOD OF CONVEYING CIGARETTES THROUGH CIGARETTE - PACKING MACHINES

Vladimir Dmitrijevic Popov, Prague-Bubenec,
Czechoslovakia

Application January 20, 1933, Serial No. 652,649
In Czechoslovakia June 13, 1932

3 Claims. (Cl. 226—5)

This invention relates to a method for use in conjunction with cigarette-packing machines for conveying the cigarettes from the hopper or storage chamber of the machine to the stack-ways or feed passages, and thence into the boxes.

The hitherto known methods of conveying and conducting cigarettes from the supply container to the packing mechanism proper of a packing machine require various types of shaking mechanism adapted to maintain and assist the mobility of the cigarettes and to facilitate the gradual feed movement of the same from the storage chamber to the stack-ways or feed passages leading to the boxes to be filled. The means employed for this purpose consist, depending on the system under consideration, of movable walls for the passages proper, or oscillatory or rocking elements upon which the cigarettes are caused to travel towards the feed passages, or milled rollers which rotate constantly in one direction, and which are adapted to impart movement to the cigarettes by virtue of their milled or finely grooved surfaces. It has also been proposed to employ rocking walls and milled rollers in various combinations. The most serious objections to all such arrangements are the frequent deformation of the cigarettes and the shaking out of the tobacco caused thereby, it not having been possible hitherto to eliminate these drawbacks.

The method according to the present invention entirely avoids any shaking of the cigarettes, and thus precludes the possibility of the deformation of the cigarettes and effectually prevents the shaking out of the tobacco.

With the method according to the present invention, the cigarettes pass out of the main storage chamber into a lower chamber through apertures formed between plain smooth rollers adapted to be rotated periodically through a certain angle alternately in both directions. From the lower chamber, the cigarettes pass in the same manner into a bottom chamber, and from the latter into the feed passages. The oscillating movement of the smooth rollers prevents arches of cigarettes forming over the individual apertures to be traversed by the cigarettes. Such arches would check the free passage of the cigarettes from one chamber to the other and into the feed passages. In the final chamber above the feed passages, in accordance with the present invention, the cigarettes are given the greatest freedom of movement, that is to say they may be displaced most readily so as to find their way in running succession into

the feed passages. At the same time the cigarettes are effectually prevented from becoming compressed at this stage, or from becoming jammed and blocking the feed passages.

A form of construction of a device for the carrying out of the method according to the invention is illustrated, by way of example, in the accompanying drawing, in which:—

Fig. 1 shows the device in longitudinal section.

Fig. 2 is a side elevation in part section of the lower portion of the device shown in Fig. 1 with a box positioned in readiness to receive a charge of cigarettes from the feed passages.

In Fig. 1 of the drawings A denotes the main storage chamber or hopper, which may be of any desired dimensions. The floor is formed of smooth rollers 2a, 2b, 2c between which there are gaps or apertures 3a and 3b. The smooth rollers 2a, 2b, 2c are rotated periodically through a certain angle in both directions, their drive being taken from a shaft 4 which is driven, through the intermediary of a belt 5 and of a belt pulley 6, from a motor or from any suitable part of the packing machine. To the shaft 4 there is keyed a crank arm 7 which operates by means of the connecting rod 8 the crank arm 9 attached to the pin 10a on the smooth roller 2a. The toothed wheel 11a, which is attached to the pin 10a, meshes with the toothed wheel 11b on the pin 10b of the shaft 2b, whence the movement is likewise transmitted to the toothed wheel 11c on the pin 10c. There is further attached to the pin 10a a toothed wheel 12 which engages the wheel 13a; by this latter wheel the movement is transmitted to the toothed wheel 13b which, in its turn, meshes with the wheel 13c. The crank arm 7 imparts to the roller 2a a periodic movement in alternate directions, and this movement is transmitted by the described arrangement of wheels to all the remaining rollers in both rows.

The cigarettes placed in bulk in the chamber A bear at the bottom thereof against the smooth rollers 2a, 2b, 2c, but are prevented by the periodically alternating rotary movements of these rollers from forming arches over the gaps 3a and 3b, and pass through these latter into the chamber B. The bottom of the chamber B is formed by the smooth rollers 14a, 14b, 14c which are caused to move in precisely the same manner as the rollers 2a, 2b, 2c. Between the rollers 14a, 14b, 14c there are left openings 15a, 15b which are narrower than the openings 3a, 3b. Through the openings 15a, 15b the cigarettes pass one by one into the chamber C. The above-

described arrangement and construction of the parts of the device ensure that the pressure of the quantity of cigarettes piled up in the chamber A is brought to bear only to quite a slight extent on the cigarettes in the chamber B, and practically not at all on the cigarettes in the chamber C. The cigarettes in the chamber C are thus not pressed together or compressed at all, and are therefore also very mobile. The top of the chamber C is formed of the oscillating smooth rollers 14a, 14b, 14c which not only prevent the jamming of the cigarettes above the passages D₁, D₂, etc., but actually force or "coax" the cigarettes into the individual stack-ways or feed passages D₁, D₂, D₃, D₄, and D₅. Nevertheless it is conceivable that with the arrangement as described the cigarettes in the chamber C could assume such positions that the opening into one or more of the feed passages becomes blocked (compare the position of the cigarettes 18 and 19 above the passage D₄). These two cigarettes 18 and 19 are resting on the walls of the passage D₄ out of reach of the roller 14a, and can thus remain stationary in this position, irrespective of the movement of this roller. As long as these cigarettes remain in this position the passage D₄ is blocked and cut off from the cigarette stream. In order to prevent the cigarettes from assuming such positions except for a very short time the cigarettes are caused to pass from the chamber B into the chamber C not only through the upper openings or gaps 15a, 15b, but also from the side through the channels 16a, 16b, in the direction of the arrows e and f (Fig. 1). The cigarettes coming in from the side exert lateral forces which tend to move any cigarettes bearing against the walls of the feed passages either to one side or to the other, wherever there is more free space. As can be seen in Fig. 1, the lateral force exerted in the direction of the arrow f disturbs the state of rest of the cigarettes 18 and 19 above the passage D₄ by causing the same to be more or less displaced by the cigarettes above the passage D₅. In this manner the stationary cigarettes are brought out of their state of equilibrium, are moved to the left and drop into the passage D₄ which then continues to be filled with cigarettes in the normal manner after a very short interruption.

From the above description it will be clear that the main flow of the cigarettes from the chamber B into the chamber C is vertical through the openings 15a and 15b, while the passage of the cigarettes through the channels 16a and 16b in the direction of the arrows e and f is of but slight extent, and is only necessary to effectually counteract any tendency for the cigarettes to become stationary on top of the walls or partitions between the feed passages, and thus to ensure the correct and suitable functioning of the device.

In order to ensure that the cigarettes from the chamber C shall fill the passages D₁, D₂, etc., the height of the chamber C must be kept low

and should ideally be such that the cigarettes which touch the oscillating rollers 14a, 14b, 14c at the top are caused to move to the right or to the left solely by virtue of friction against these rollers, and then drop into the passages by virtue of their inherent weight. If the height of the chamber C be increased beyond the correct amount the reliability of the feed movement of the cigarettes into the stack-ways D₁—D₅ is reduced, and wrong dimensioning is capable of robbing the chambers C entirely of their efficiency for the intended purpose. 5 10

An important condition for the required mobility of the cigarettes in the chamber C is the manner in which this chamber C is filled with cigarettes through the openings 15a, 15b, and channels 16a, 16b. 15

The breadth of the openings 15a, 15b, and of the channels 16a, 16b must be such that the cigarettes pass therethrough into the chamber C one at a time, it being thus ensured that almost every cigarette which passes into the chamber C comes into contact with the smooth surface of the oscillating rollers, and that the direction of the subsequent movement of the cigarettes is determined by their inherent weight. 20 25

From the passages D₁, D₂, etc., the cigarettes can be ejected in groups, for instance of five, by the ejector E into the boxes F (Figs. 1 and 2). The cigarettes thus removed from the passages 30 are at once replaced by fresh cigarettes coming in from the chamber C. It is to be understood that the cigarettes can be transferred from the passages D into the boxes F in a different manner, in a different number, and in a different 35 arrangement from that shown in the drawings.

I claim:

1. In a cigarette packing machine, a storage container for cigarettes, a plurality of vertical feed passages below said container, a row of 40 rollers between said storage container and said passages and spaced from one another and from the entrance openings of said passages a distance slightly greater than the diameter of a cigarette, means for conveying cigarettes from 45 the storage container to said rollers, and means for rotating said rollers back and forth.

2. A cigarette packing machine according to claim 1, characterized by stationary walls partly surrounding each end roller and forming channels the height of which is slightly greater than the diameter of a cigarette and opening at one end into the space between the storage container and the rollers and at the other end into the space between the rollers and the passages at 55 substantially a right angle to said passages. 50

3. A cigarette packing machine according to claim 1, characterized by a row of rollers between the storage container and said first mentioned rollers and which are spaced from one another and from the first mentioned rollers a distance greater than two cigarettes, and means for rotating back and forth said last mentioned rollers. 60
